UNITED STATES PATENT OFFICE.

PAUL GRENVILLE MERRITT, OF NEW ORLEANS, LOUISIANA, ASSIGNOR OF ONE-FOURTH TO JOSEPH CHARLES TREMOULET, OF NEW ORLEANS, LOUISIANA.

APPARATUS FOR DISPENSING TOWELS, NAPKINS, AND THE LIKE.

1,057,973.

Specification of Letters Patent.

Patented Apr. 1, 1913.

Application filed February 20, 1912. Serial No. 678,802.

To all whom it may concern:

Be it known that I, PAUL G. MERRITT, a citizen of the United States, and a resident of New Orleans, in the parish of Orleans and State of Louisiana, have invented a new and Improved Apparatus for Dispensing Towels, Napkins, and the Like, of which the following is a full, clear, and exact description.

10 The object of the present invention is to provide an apparatus for containing and dispensing towels, napkins and similar articles as they are required for use, and more particularly to contain and dispense such articles assembled in the form of rolls, such rolls of articles being produced by the rolling apparatus forming the subject matter of an application filed of even date herewith.

Reference is to be had to the accompanying drawings, constituting a part of this specification, in which similar characters of reference denote corresponding parts in all the views and in which—

Figure 1 shows the apparatus in front elevation with the door of the casing opened to show the interior; Fig. 2 shows a vertical sectional view showing a plurality of rolls contained therein, and illustrating the operation of the dispensing mechanism; Fig. 3 shows a similar view illustrating the means whereby an emptied roller may be discharged and replaced by a full one; Fig. 4 shows a perspective of a detail of the releasing mechanism.

35 The apparatus comprises a retaining case 1, which, in the illustrated embodiment of the invention, is shown as a wall cabinet, but which obviously may be constructed as a built-in part of the wall.

40 As shown in the drawing, the cabinet 1 is provided with a back 2, a top shelf 3, and a bottom shelf 4, side walls 5 and 6, and a door 7 swinging upon hinges 8. There is thus formed a main chamber 9, and below the

45 shelf 4, there is a supplemental chamber 10 closed by a door 11 hinged at 12 and normally held closed by means of a lock or latch 13. The main chamber 9 contains the roll of towels, napkins or other articles to be

50 dispensed, and the articles are rolled upon a roller 14, the ends of adjacent articles overlapping, so that in drawing one of such articles off the roll, a portion of the free end of the next adjacent article will be slightly drawn off.

The roller 14 is arranged to be received between vertical guides 15 and 16 secured to the inner surface of the side walls 5 and 6 of the chamber 9. The guides 15 and 16 are spaced apart a distance substantially 50 equal to the diameter of the rollers 14, so that said rollers may be retained by said guides and permitted to revolve freely as the towels or napkins are drawn therefrom.

For the purpose of admitting the rollers 65 14 between the guides 15 and 16, the upper end of the guide 15 terminates as shown at 17 at a point below the top or shelf 3 a sufficient distance to permit the insertion of a filled roller at the top of the guides, and in 70 order to permit the escape of an emptied roller from the guides, the lower end 18 of the guide 16 terminates at some distance above the shelf 4, thus leaving a space at the back whereby the emptied roller may pass 75 out of the guides and fall into the chamber 10, the shelf 4 being cut away at its rear edge as shown at 19, forming a space 20 leading into the chamber 10.

The casing 9 may be of such height as 80 required, but it will probably be of sufficient height to accommodate a plurality of rolls of towels or napkins as shown in the drawing, they being arranged in vertical alignment with each other, with the ends of the 85 rollers 14 retained in the space between the guides 15 and 16, and arranged to drop by gravity therein. The lower roll rests upon a swinging shelf 21 pivotally mounted at 22 to standards 23, and arranged to swing from 90 the position shown in full lines, Fig. 2, to a position shown in full lines, Fig. 3, and when in the position shown in Fig. 2, the pivoted shelf 21 retains the rolls in the guides and in position for delivering the articles from the lower roll at the same time exerting pressure or tension against the roll of towels or napkins.

The articles as they are drawn off of the rolls pass over the upper surface of the pivoted shelf 21 and through an opening or space 24 beneath the lower edge of the door 7, and the forward edge of the shelf 4 as indicated by the letter *t* in Fig. 2. With the parts in the position shown in Fig. 2, when 100 it is desired to secure a towel or napkin from the dispensing apparatus, the free edge of the towel *t* is grasped and drawn through the slot or opening 24, the lowermost roller revolving as the towel is drawn therefrom, 110

and as the towel is removed from the casing, the end of the next adjacent towel will be drawn out and remain in the position shown in Fig. 2 ready to be grasped and removed when desired.

In order to retain the upper rolls in an inactive position so that the roll next to the one being unrolled will not contact therewith, and in order that the lowermost roll in a plurality of rolls may be cut out as desired and the rolls fed to an operative position, one at a time, there is provided a suitable cut out and retaining mechanism comprising a pair of levers 25 pivotally mounted at 26, which levers at their upper ends are provided with curved arms 27, and at their lower ends with the reversely extending hooks 28. The hooks 28 support the ends of the roller 14 of the roll of towels next adjacent to that roll being unrolled, until such time as it is desired to release this second roll of towels and permit it to drop into operative position. When it is desired to secure this result, the levers 25 are rocked to the position shown in full lines in Fig. 3; thus the hooks 28 are withdrawn from beneath the roller 14 and permits this second roll of towels to drop into the position for dispensing the articles contained thereon.

It is desired that only one roll be dropped at a time, and therefore, as will be shown from Fig. 3, the withdrawal of the hooks 28 from engagement with the ends of the roller 14 of the second roll in the line of rolls, simultaneously causes the curved arms 27 to be interposed beneath the ends of the roller 14 of the top roll, as shown in Fig. 3. After the roll is dropped to operative position, the levers 25 will be swung in the reverse direction to the position shown in dotted lines in Fig. 2, thus throwing the hooks 28 into position to catch and support the top roller in an intermediate position, and the curved arms 27 simultaneously releases the top roller, permitting it to drop.

In order to swing the levers 25 and their retaining arms and hooks, there are provided links 30 which are pivotally connected at 31 to the curved arms 27 of the levers 25, and also pivotally connected at 32 to the crank arms 33 of a rock shaft 34 which supports the swinging shelf 21. At one end, one of the crank arms 33 is provided with a laterally projecting arm 35 passing through a slotted plate 36 in the side wall 5 of the casing, and provided upon the outside of the casing with a handle 37, whereby the rock shaft may be turned and the links 30 operated to rock the shelf 21 and the levers 25 to discharge an emptied roller into the lower chamber 10, and to release and drop into operative position, a full roller as hereinbefore set forth. The slot in the plate 36 at its lower end is provided with a notch or shoulder 38 with which the arm 35 may be

engaged to hold the parts in the position shown in Fig. 2.

In operation, assuming that the apparatus has been provided with a plurality of rolls of towels or napkins, (the one shown in the drawing having a capacity of three of such rolls), the rolls will be supported in vertical alinement with each other with the rollers 14 fitting the space between the guides 15 and 16, and as shown in Fig. 2, the lowermost roller will rest upon the pivoted shelf 21 with the leading towel passing over the said shelf and projecting as shown at 5. The second roll will be supported by the hooks 28 assuming that the first roller has been reduced in diameter by the withdrawal of towels. As the towels are drawn off of the lowermost roller 14, it will drop downward toward the pivoted shelf 21, and when emptied, it will rest in the position shown in dotted lines in Fig. 2. At this time, an upward movement of the links 30 will lift the shelf 21 at its forward end and depress it at its lower end, permitting the roller which has been emptied to pass through the opening 19 at the back of the shelf 4, and drop into the chamber 10, as shown in dotted lines in Fig. 3. Simultaneously with the upward movement of the forward end of the shelf 21, the levers 25 will be rocked to the position shown in Fig. 3, thus releasing the roller of the middle roll of towels, and permitting it to drop to the lowermost position, while at the same time, the curved arms 27 will engage the ends of the roller 14 of the top roll and prevent its dropping. After the new roll has fallen into position, the shelf 21 is turned to the position shown in Fig. 2, whereupon the top roll of towels will be released by the curved arms 27, and will drop to the intermediate position supported by the hooks 28, and the apparatus is again equipped for a further operation.

Having thus described my invention, I claim as new and desire to secure by Letters Patent:

1. In an apparatus of the class described, a casing having guideways, a plurality of rolls of towels or napkins disposed in the guideways of the casing one above the other, and means for supporting the roll next to the lowermost one out of contact therewith and releasing the same to allow it to move to operative position when the towels or napkins have been drawn off from the said lowermost roll.

2. In an apparatus of the class described, a casing having guideways, a plurality of rolls of towels or napkins disposed in the guideways of the casing one above the other, and means for alternately supporting and releasing the two rolls next above the lowermost roll.

3. In an apparatus of the class described, a casing having vertical guideways, a plu-

rality of rolls of towels or napkins disposed in the guideways one above the other, a swinging shelf upon which the lowermost roll rests, means for alternately supporting 5 and releasing the two rolls next above the lowermost roll, and a connection between the said means and shelf.

4. In an apparatus of the class described, in combination, a chamber, vertical guides 10 located at opposite ends of said chamber, a plurality of rolls of towels supported in vertical alinement with each other in said guides, a swinging shelf supported at the

lower end of said guides, and a pair of levers having at their lower ends detaining 15 hooks, and at their upper ends curved guides, and means connecting the swinging shelf with the pair of levers whereby the shelf and levers are simultaneously operated.

In testimony whereof I have signed my 20 name to this specification in the presence of two subscribing witnesses.

PAUL GRENVILLE MERRITT.
